LADY'S REVERSIBLE HANDBAG

George H. Khoury, Corona, N. Y.

Application May 17, 1943, Serial No. 487,388

3 Claims. (Cl. 150—28)

This invention relates to improvements in ladies' accessories, and more particularly to improvements in hand bags conventionally carried by ladies.

The wardrobe of every well-dressed woman comprises a plurality of dresses of different colors and patterns, as well as a plurality of different coats. Inasmuch as fashion dictates that accessories used harmonize with each dress or coat, or carry out some predetermined color scheme, it is necessary that a woman, to be well-dressed, own several hand bags. Ownership of a plurality of such hand bags has however been found to be a costly matter, and the necessity of transferring the contents of one bag to another is recognized by women to take up considerable time and effort.

Therefore, it is the chief aim of my invention to provide a reversible hand bag, which may be carried with its inner or outer face exposed.

It is a further advantage of my invention to provide a hand bag the inner face of which differs from its outer face in color, design, pattern, material or in any other desirable way, and to provide means for reversing the bag so that either its inner or its outer face may be exposed.

A still further purpose of the present invention resides in the provision of a reversible hand bag made of a unitary piece of material, each side of the bag being provided with a retaining member, which may be removed and replaced at will, so that the bag may be reversed.

Yet another aim of this invention lies in the provision of a reversible hand bag of simple construction, relatively inexpensive to manufacture, and which is highly efficient in its use.

And it is yet another object of the present invention to provide a hand bag of this character, which may be reversed in a few minutes, without the use of any tools and without requiring any skill.

These and other meritorious objects and advantages, which will become more fully apparent as the description hereof proceeds, are accomplished by the novel construction, combination and arrangement of few and simple parts, hereinafter described and illustrated in the accompanying drawing, constituting a material component of this disclosure, and in which:

Figure 1 is a front elevational view of a reversible hand bag, constructed in accordance with the present invention, the flap or cover portion being open.

Figure 2 is a sectional view of the device, the section being taken on line 2—2 of Figure 1.

Figure 3 is a perspective view of the device, partly open and partly exploded, to show the relative arrangement of the several parts; and

Figure 4 is a front elevational view of a modified form of this invention.

Referring in greater detail to the drawing, the hand bag 10 illustrated in Figures 1 to 3 inclusive is of the type commercially referred to as an "envelope bag," and comprises an outer face 11, an inner face 12, a flap or cover portion 13 and a substantially flat bottom 32. This bag may be made of leather, cloth, patent leather or any other desirable and suitable fabric. As is best illustrated in Figure 3, bag 10 is made of a unitary material, flap 13 being demarcated from the body of the bag by a crease line, and the body being demarcated by crease lines in the well-known and conventional manner to form the bottom 32. An intermediary section 14 is formed between the horizontal end of the cover 13 and the horizontal upper edge of the bag to permit the cover to overlap the bag when it is closed. This too is a conventional expedient.

Beginning at the crease line which separates the intermediary section 14 from the body of bag 10, and extending downwardly to the lower edge of the bag, the fabric is turned inwardly upon itself throughout the length of the bag and secured thereto by stitching, gluing, pasting or in any other suitable manner, to form narrow vertical beads 15 and 16 respectively, one on each side of the bag, the vertical beads being of hollow interior and forming a housing for strings 19, 20, 21 and 22, the strings serving as guides as will hereinafter become apparent. The said guide strings extend upwardly beyond the upper edge of the bag and may be secured in the beads by stitching, gluing, pasting or otherwise.

There are provided two retaining members 17 and 18 respectively, one for each side of the bag. Retaining members 17 and 18 may be made of wood, plastic or any other desirable and suitable composition. Retaining members 17 and 18 are substantially rectangular in cross-section and of relatively narrow width. Throughout its entire length, each longitudinal edge of members 17 and 18 is provided with a groove, as is indicated at 23, 24, 25 and 26, the grooves being wide enough to accommodate beads 15 and 16 respectively, which are adapted to be entered therein. The grooves terminate in arcuate openings 27, 28, 29 and 30 the purpose of which will presently be explained. A conventional press-button 31 and its female counterpart 32 may be provided to close the cover 13.

The modified form illustrated in Figure 4 comprises a bag 50 similar to bag 10, except that no cover member such as 13 is provided. Instead, there is provided a clamping element 40, pivotally secured at the center of the bag near the upper edge 51 thereof, as is indicated at 43. Clamp 40 has a horizontal groove throughout its top, as at 41, and a similar groove at its bottom, indicated by the numeral 42. Retaining members 44 and 45, provided with vertical grooves which terminate in arcuate openings 46, 47, 48 and 49 do not differ from retaining elements 17 and 18 hereabove described, hence require no further description here.

In operation, when it is desired to reverse the bag illustrated in Figure 1, so that the inner face 12 will be exposed, bows 33 and 34 are untied, the bag held in one hand, while retaining elements 17 and 18 are pulled upwardly, one at a time to disengage vertical beads 15 and 16 from grooves 23, 24, 25 and 26. The bag is then folded upon itself by swinging it outwardly, until the position indicated in dotted lines in Figure 2 of the drawing is achieved. Each retaining member is then replaced separately. Guide strings 19 and 20 are then entered into grooves 23 and 25 respectively, and the retaining member 17 caused to slide downwardly upon these guide strings until the bottom of member 17 makes contact with the upper edge of bead 15, whereupon the bead is forced into the lower end of the grooves 23 and 25. The retaining member is then caused to slide along the bead, by pulling the strings upwardly, until it reaches the bottom portion 32 of the bag, whereupon the ends of the guide strings 19 and 20 are tied into a bow or otherwise secured. Member 18 is re-inserted in a like manner.

The form illustrated in Figure 4 differs only in that no cover is used. Instead there is employed a pivotally secured clamp, which will close the bag in the manner illustrated in Figure 4 when the bag is in one position, and when the bag is in reversed position, groove 40 will engage the upper edges of the bag instead of groove 42.

Many modifications of this bag are apparent, and others will be seen as occasions arise. For instance, instead of employing four guide strings 19, 20, 21 and 22, two such strings may be employed, one for each side of the bag, the ends of which will extend beyond the bag, in the same manner as is here illustrated. Instead of strings, it may be desirable to use link chains or other more ornamental guide elements. Instead of securing clamp 40 to the bag, a conventional upper frame may be used, to which clamp 40 may be pivotally secured. Also it may be desirable to eliminate retaining members 17 and 18 and in their stead reversible "Zippers" may be used to achieve the same end. Cover fastening means

other than snap buttons may also be employed. The bag itself may be made of any desirable material, and the inner face may differ from its outer face either in color, material, shading design etc. A change purse may be provided by securing a small hook to each retaining member, and a change purse or compact and rouge pouch mounted on a chain may be secured between these hooks and easily removed when it is desired to reverse the bag.

Thus there have been shown and described the preferred embodiments of a simple, yet highly efficient reversible bag. This disclosure however is to be regarded as illustrative and descriptive of the preferred embodiments and not as limitative or restrictive to the exact details shown. Applicant reserves the right to make such changes and modifications in the construction of his device as come within the scope of the appended claims without thereby departing from the spirit of this invention.

What is claimed as new and desired to secure by Letters Patent, is:

1. In combination with a reversible bag comprising a unitary piece of material divided by crease lines to form the front, back, bottom and cover flap, a narrow vertical bead formed at each longitudinal edge of said material throughout the length of said front, back and bottom forming a pair of longitudinal beads, a pair of substantially rectangular side elements, and a vertical groove having a restricted opening throughout each longitudinal edge of said side elements in which said beads are adapted to be removably retained to form a bag.

2. In combination with a reversible bag comprising a front, back, bottom and cover flap, a pair of beads formed integrally therewith, each of said beads formed respectively throughout each vertical edge of said front and back, a pair of side elements, each of said side elements substantially rectangular in cross-section, each of said side elements provided with a pair of grooves having restricted openings, one throughout each vertical edge of each of said side members, said beads adapted to be removably retained in said side members to form a bag.

3. In combination with a reversible bag comprising a front, bottom, back and cover flap, the longitudinal edges of said front, bottom and back formed each with an integral hollow, vertical bead, a guide strap in each vertical bead, a pair of narrow side elements of rectangular cross-section, and a vertical groove throughout each vertical edge of each of said side elements, said beads adapted to engage said grooves to form a bag.

GEORGE H. KHOURY.
